[57] CLAIM

The ornamental design for a magnetic tape transport, as
shown and described.

DESCRIPTION

FIG. 1 is a top plan view of a magnetic tape transport
showing my new design;

FIG. 2 is a perspective view from the top and one side
thereof, on a reduced scale;

FIG. 3 is an elevational view of the side opposite that
shown in FIG. 2;

FIG. 4 is an end elevational view thereof as seen from
the right of FIG. 1;

FIG. 5 is an end elevational view thereof as seen from
the left of FIG. 1;

FIG. 6 is a perspective view from the top and the side
shown in FIG. 3 on a reduced scale.

FIG. 1

FIG. 2

FIG. 3

FIG. 4

FIG. 5

FIG. 6
